the claim. The long-dash short-dash broken lines indicates cutoff boundaries for enlarged detail portion views and form no part of the claim.

The back view is omitted because it is a mirror image of the front view; the left side view is omitted because it is identical to the right side view; reproduction 1.12 is the front view showing a constituent member of the mechanical joint; reproduction 1.13 is the top view showing a constituent member of the mechanical joint; reproduction 1.6 is a cross-sectional view taken along line 1.6-1.6 of reproduction 1.4; reproduction 1.7 is a cross-sectional view taken along line 1.7-1.7 of reproduction 1.4; reproduction 1.8 is a partially enlarged cross-sectional view of 1.8-1.8 region in reproduction 1.6; reproduction 1.9 is a partially enlarged cross-sectional view of 1.9-1.9 region in reproduction 1.7; reproduction 1.10 is a partially enlarged cross-sectional view of 1.10-1.10 region in reproduction 1.8; reproduction 1.11 is a partially enlarged cross-sectional view of 1.11-1.11 region in reproduction 1.9; reproduction 1.14 is a cross-sectional view taken along line 1.14-1.14 of reproduction 1.13; reproduction 1.15 is a cross-sectional view taken along line 1.15-1.15 of reproduction 1.13; reproduction 1.16 is a partially enlarged cross-sectional view of 1.16-1.16 region in reproduction 1.14; Reproduction 1.17 is a partially enlarged cross-sectional view of 1.17-1.17 region in reproduction 1.14; reproduction 1.18 is a partially enlarged cross-sectional view of 1.18-1.18 region in reproduction 1.15; reproduction 1.19 is a partially enlarged cross-sectional view of 1.19-1.19 region in reproduction 1.15; reproduction 1.20 is a partially enlarged cross-sectional view of 1.20-1.20 region in reproduction 1.16; reproduction 1.21 is a partially enlarged cross-sectional view of 1.21-1.21 region in reproduction 1.17; reproduction 1.22 is a partially enlarged cross-

sectional view of 1.22-1.22 region in reproduction 1.18; reproduction 1.23 is a partially enlarged cross-sectional view of 1.23-1.23 region in reproduction 1.19.
